UNITED STATES PATENT OFFICE.

WILLIAM A. LORENZ, OF HARTFORD, CONNECTICUT.

DESIGN FOR A CAN OR JAR.

SPECIFICATION forming part of Design No. 35,367, dated December 3, 1901.

Application filed August 12, 1901. Serial No. 71,850. Term of patent 14 years.

To all whom it may concern:

Be it known that I, WILLIAM A. LORENZ, a citizen of the United States, residing in Hartford, in the county of Hartford and State of Connecticut, have invented and produced a new and original Design for Cans or Jars, of which the following is a specification.

ing ribs 13, terminating in the projecting lobes at the edges of the leaf.

Having described my invention, what I claim as new, and desire to secure by Letters Patent, is—

20

The design for a can or jar substantially as shown and described.

In testimony whereof I have signed my name to this specification in the presence of two subscribing witnesses.

WILLIAM A. LORENZ.

Witnesses:

HANS MALLNER,
NELLIE PHOENIX.

My design relates to the external ornamentation of cans, jars, and similar receptacles.

10 Figure 1 of the drawings is a plan view, and Fig. 2 a side view, of a can or jar embodying my design.

The approximately cylindrical body 10 of the jar is provided with the representation of 15 a palm-leaf 11, having a stem 12 and radiat-
